LYMAN C. JOSEPHS, JR., OF ALLENTEWON, PENNSYLVANIA, ASSIGNOR TO INTERNATIONAL MOTOR COMPANY, OF NEW YORK, N. Y., A CORPORATION OF DELAWARE.

INTERLOCK DEVICE FOR RAIL-CAR-CONTROL SYSTEMS.

Application filed January 14, 1925. Serial No. 2,439.

This invention is concerned particularly with suitable interlock devices for the control elements on a rail car propelled by an internal combustion engine. The conditions of operation surrounding such rail cars and the interlock to be effected are peculiar to the presence of a controlling device for the speed of the internal combustion engine, a controlling device for the transmission clutch and brakes and a reversing device for establishing proper conditions for operation of the last named controller depending upon the direction of travel of the car. When the operator of such a car leaves his post it is desirable that the reversing mechanism, as well as the control for the transmission etc., should be interlocked in "off" position so that they may not be moved surreptitiously and in some cases it is desirable in addition to interlock therewith the speed control for the engine while permitting it to idle. On the other hand, there are conditions where with the reverse and the transmission control interlocked it is desirable to leave the speed control for the engine free so that it may be operated at different speeds without hindrance at times while the operator is away from his station. This last named condition arises, for instance, when the operator needs to test the motor and perhaps inspect it while under the car or in some other dangerous position.

In accordance with the present invention it is proposed to provide an interlock means which shall be of simple and positive nature and operable automatically when the parts are in predetermined relation to hold the reverse control and the transmission control against surreptitious movement when the operator leaves them. A further object of the invention is to provide a supplemental interlock releasable automatically with the first named interlock device for holding the engine speed control means against movement when the engine is set for idling while permitting free manipulation thereof at all other engine speeds. These and other objects of the invention will appear more clearly hereinafter in connection with the detailed description illustrated in the accompanying drawings, wherein:

Figure 1 is a fragmentary view in elevation showing somewhat conventionally suitable control means for a rail car which is

propelled by an internal combustion engine 55 with the improved interlock operatively associated therewith.

Figure 2 is a view in horizontal section through the parts shown in Figure 1 with the throttle control interlocked for idling 60 of the engine.

Figure 3 is a detailed view in plan of the interlock bar and showing in section the relation thereto of the pivoted interlock for the throttle.

By way of illustration, but not limitation, there is shown in the drawings in elevation suitable mechanism for operating a self-propelled rail car the drum *a* at the right in Figure 1 being of such a nature as 70 to permit the operator to effect necessary operations such as throwing a clutch, shifting gears or other change speed media and the like, the drum *b* at the left being of such a nature as to permit the operator to check 75 conditions in such control devices upon reversal of direction of travel and the shaft *c* being, for instance, a controlling shaft for speed of the prime mover, such as, for instance, the throttle valve of an internal combustion engine. The principal object of the present invention is to bring the mechanism just referred to briefly in such relation as to permit desirable conditions of safety to be established conveniently by the operator as, 85 for instance, when he leaves his post. These conditions are conceived to be generally as follows:

With the reverse control *b* in "off" position the controlling mechanism *a* should be 90 automatically locked against surreptitious movement; with the aforementioned mechanism in such interlocked relationship the speed control *c* for the prime mover should be either (a) interlocked therewith with the 95 prime mover idling at predetermined speed or (b) manipulable freely at all speeds above such predetermined speeds so that the prime mover might be freely controlled while locomotion of the vehicle is positively 100 guarded against by interlock of the elements *a* and *b*.

The desirable relationship described is accomplished simply and positively in the preferred embodiment of the present invention by means of a lever *d* pivoted at *d'* and having at one end a nose *d''* to engage a recess *a'* formed in a plate *a''* movable with

the drum a and at the other end an anti-friction member d^3 adapted to roll on the bottom of a plate b' movable with the reverse mechanism b . The plate b' has recesses b^2 in its underface which the roller d^3 may enter, these recesses being brought into alignment with the roller when the reverser is either set for operation of the vehicle in one direction or the other. A suitable spring 5 e co-operates with the lever d to force the roller d^3 into one or the other of the recesses b^2 thereby withdrawing the other detent end d^2 from the recess a' in the plate a^2 . When the reverser is in any other than operating 10 position the under surface of the plate b' forces the end of the lever d downwardly against the action of the spring e and maintains the end d^2 within the recess a' provided the controller drum a is in "off" position. In this way, the controller a is held 15 against surreptitious movement when the reverse mechanism is also in "off" position. The reverser, as usual, may have at its upper end a squared shaft b^3 with which the operator engages a specially formed controller handle intended to be carried with him whenever he leaves his post.

Under some circumstances it is desirable 20 to lock the prime mover, such as an internal combustion engine, against surreptitious manipulation and accordingly in the improved construction a detent f is pivoted on the pin d' and pressed yieldingly by a suitable spring such as g towards a slotted collar 25 c' carried on the shaft c , the slot c^2 in said collar being brought opposite to the detent f when the engine is in desired idling condition. The spring g at such a time forces the detent f into the slot c^2 and the shaft c 30 is held against movement. Under other conditions, however, it may be desirable to make it possible for the operator to run the prime mover at different speeds even though the control mechanism a is interlocked with 35 the reverser b so as to hold the vehicle against locomotion. The construction illustrated permits this condition in that so long as the engine is operated at a speed above the predetermined idling speed the slot c^2 40 will not be carried into alignment with the detent f and the nose of the detent will be pressed yieldingly against the surface of the collar c' without interfering with oscillation of the shaft c . A convenient and automatic 45 release of the detent f when in engagement with the slot c^2 is provided through an adjustable set screw f' carried with the pivoted detent f and engageable at its lower end with the interlocked lever d whereby when 50 the reverser b is moved into one or the other of its operating positions and the spring e becomes effective to lock the lever d and withdraw the nose d^2 from engagement with the plate a^2 on the drum a , the lever f will 55 simultaneously be rocked in a clockwise di-

rection against the action of the spring d to withdraw its nose from engagement with the collar c' . The conditions afforded meet, it is believed, those necessary under practical road conditions, particularly for rail cars 60 propelled by internal combustion engines. For instance, if the attendant desires to inspect the motor he may want to interlock the controls so that the car may not be surreptitiously started while he is away from his post and, perhaps, under the engine. At the same time, he may want to run the engine at different speeds by direct manipulation of its throttle valve. This will not be interfered with by the interlock for the 65 throttle operating shaft c . Under other conditions when leaving his post he may desire to interlock the throttle shaft c with the other mechanism while leaving the motor idling. At such a time, he will take with 70 him his operating lever for the reverser b .

It is to be understood that the invention is not to be limited to the particular nature of the controls provided nor the details of construction of the interlock elements 75 so long as the general conditions provided for are obtained by mechanically equivalent means.

What I claim is:

1. In a vehicle provided with control 80 mechanism for regulating the speed of the prime mover, control mechanism for controlling the vehicle speed independently of the speed of the prime mover, and reverser mechanism changing the conditions of control depending upon the direction of travel of the vehicle, interlock means operable automatically to secure the controlling mechanism against surreptitious operation when the reverse mechanism is in "off" position, 85 means operable automatically when the prime mover is in idling position and the reverser is in "off" position to lock the speed controlling means for the prime mover.

2. In a vehicle provided with control 90 mechanism for regulating the speed of the prime mover, control mechanism for controlling the vehicle speed independently of the speed of the prime mover, reverser mechanism changing the conditions of control depending upon the direction of travel of the vehicle, interlock means operable 95 automatically to secure the controlling mechanism against surreptitious operation when the reverse mechanism is in "off" position, means operable automatically when the prime mover is in idling position and the reverser is in "off" position to lock the speed controlling means for the prime mover, and means co-operating with said last named 100 means to permit free operation of the speed control devices above predetermined idling speeds when the reverser is in "off" position.

3. In a rail car propelled by an internal 105 combustion engine, a throttle control for the 110

engine, a change speed control for the vehicle, and a reverser, interlock mechanism between the reverser and the change speed mechanism including a lever engageable with the change speed mechanism when the latter is in "off" position and the reverser is in "off" position and means operated by said interlock mechanism to lock the throttle control means including means to prevent operation of the throttle locking means over a desired range of movement of the control.

4. In a rail car propelled by an internal combustion engine, a throttle control for the engine, a change speed control for the vehicle, and a reverser, interlock mechanism between the reverser and the change speed mechanism including a lever engageable with the change speed mechanism when the latter is in "off" position and the reverser is in "off" position, means including a spring-pressed lever having one end operatively engaged with the reverser and the other end operatively engaged with the speed control mechanism, a spring-pressed detent pivoted with said interlock lever and adapted to engage the throttle control means when the engine is idling and the reverser is in "off" position, and means to hold said detent out of engagement with said throttle control means when the engine is operated at all speeds above idling.

the engine is idling and the reverser is in "off" position.

5. In a rail car propelled by an internal combustion engine, a throttle control for the engine, a change speed control for the vehicle, and a reverser, interlock mechanism between the reverser and the change speed mechanism including a lever engageable with the change speed mechanism when the latter is in "off" position and the reverser is in "off" position, means including a spring-pressed lever having one end operatively engaged with the reverser and the other end operatively engaged with the speed control mechanism, a spring-pressed detent pivoted with said interlock lever and adapted to engage the throttle control means when the engine is idling and the reverser is in "off" position, and means to hold said detent out of engagement with said throttle control means when the engine is operated at all speeds above idling.

This specification signed this 8th, day of January A. D. 1925.

LYMAN C. JOSEPHS, JR.
